UNITED STATES PATENT OFFICE.

EMIL LINDBERG AND GEORGE C. STEFFAN, OF JOLIET, ILLINOIS.

AUTOMATIC GATES FOR DRAWBRIDGES.

1,101,297.

Specification of Letters Patent. Patented June 23, 1914.

Application filed June 20, 1913. Serial No. 774,860.

To all whom it may concern:

Be it known that we, EMIL LINDBERG and GEORGE C. STEFFAN, citizens of the United States, residing at Joliet, in the county of Will and State of Illinois, have invented 5 certain new and useful Improvements in Automatic Gates for Drawbridges; and we do hereby declare the following to be a full, clear, and exact description of the invention, 10 such as will enable others skilled in the art to which it appertains to make and use the same.

This invention comprehends improvements in automatic gates for draw-bridges 15 and relates more particularly to those which are raised and lowered by the opening and closing of the draw.

One of the objects of the invention resides in the provision of a gate of this nature and 20 means for automatically operating the same, which shall be of extremely simple construction, efficient in operation, and very strong and durable.

With this and other objects in view as 25 will become more apparent as the description proceeds, the invention consists in certain novel features of construction, combination, and arrangement of parts, as will be hereinafter described and claimed.

30 For a complete understanding of our invention, reference is to be had to the following description and accompanying drawings, in which,

Figure 1 is a side elevation of a portion of 35 a draw-bridge equipped with our automatic gates, Fig. 2 is a fragmentary top plan view, showing the end of the draw and one of the abutments, Fig. 3 is a section taken on the plane of line 3—3 of Fig. 4, Fig. 4 is an enlarged vertical section taken on the 40 plane of line 4—4 of Fig. 2, showing the draw in its closed position, Fig. 5 is a view similar to Fig. 4 with the draw partly open, Fig. 6 is a vertical section taken on the 45 plane of line 6—6 of Fig. 3 with the standard shown in elevation, and Fig. 7 is a horizontal section taken on the plane of line 7—7 of Fig. 5, showing the manner of securing the supporting dogs.

50 Referring in detail to the drawings by numerals, 10 designates a pier which supports the draw 11, and 12 designates the piers which support the abutments 13. By referring to Fig. 2, it will be seen that the 55 draw is formed with rounded extremities which are concentric with the arcuate faces

of the abutments 13. Each of the piers 12 also carries a supporting strip or block 14 over which the extremities of the draw are positioned when the latter is closed. A plurality of metallic plates 15 are secured to the faces of the abutments and have their vertical edges spaced from one another and formed with grooves 16 so as to form guides for the gate standards 17 and 18 which are 60 provided with tongues 19 adapted to slide within said grooves. The standards 17 carry rollers 20, by means of which said standards are raised and lowered, as the draw is opened and closed. A track 21 is 65 secured to each end of the draw and forms a channel in which the rollers 20 are received when the draw is in its closed position and the gates are down. The intermediate portion 22 of each of the tracks is 70 disposed in a horizontal plane and the end portions 23 diverge upwardly and outwardly, as clearly shown in Fig. 4. It will be seen that all of the rollers 20 are positioned within the horizontal portions of the 75 channel tracks when the draw is closed. When the draw is open the inclined portions 23 will be brought into contact with the rollers 20 and slide the standards upwardly, as shown in Fig. 5. Since the tracks are 80 inclined upwardly at both ends, it is immaterial which way the draw is swung. In order to support the standards when in their raised position, we provide a plurality of dogs 24 which are pivoted within pockets 85 90 formed in the plates 15. These dogs are arranged in pairs, one pair being provided for the support of each of the standards. When the standards are raised above the dogs the latter swing by force of gravity 95 into the positions shown in Fig. 5 and have their upper edges bearing against the lower ends of the standards. When the draw is being closed the tracks 21 will receive the 100 rollers and force the standards downwardly and this downward pressure will be sufficient to swing the dogs out of the path of the standards. The dogs, however, are of sufficient weight and are so pivoted as to resist quite a strong downward force.

105 In the present instance we have shown five gates for each abutment but it is to be understood that any number desired may be employed. The inner gates of the abutments are each formed by a single post 26 which 110 is secured to a laterally extending projection 27 formed upon the corresponding

standard 17. These projections are apertured and the lower ends of the posts are extended through said apertures and secured therein by means of the pins 28. This construction makes it possible to quickly detach the gates from the standards should occasion arise for so doing. The end gates of the abutments are formed by two posts 29 which are secured to the standards 17 and 18 in a manner similar to that in which the posts 26 are connected. These gates are received within recesses formed between the plates 15 and the abutments by cutting away said abutments behind the upper portions 10 of the plates, as shown in Fig. 6. The gates carry plates 30 which lie flush with the upper surfaces of the abutments and with the upper surface of the draw when the gates are in their lowered positions. Strips 31 15 are connected to the tops of the plates 15 and serve to hold said plates in proper relation with respect to one another so that the grooves 16 will always properly receive the tongues 19 upon the standards 17 and 18.

25 From the foregoing description taken in connection with the accompanying drawing, it will be apparent that we have provided very simply constructed automatic gates for draw-bridges which will be opened and 30 closed by the action of the draw.

It is to be understood that while we have shown and described the preferred embodiment of our invention, we do not wish to be limited to this exact construction, combination, and arrangement of parts, but may make such changes as will fall within the spirit and scope of the invention as defined by the appended claims.

Having thus described our invention, we 40 claim:—

1. The combination with a draw-bridge including a draw and an abutment, of gates including a series of standards supported by said abutment and being vertically movable 45 thereon, a track secured to the draw, said track having a horizontal central portion and upwardly and outwardly extending end portions, and means carried by the gate standards for reception within said track 50 when the draw is closed, the opening of the draw causing one of the inclined portions of the track to act upon said means and raise the gate standards.

2. The combination with a draw-bridge having a draw and an abutment, of gates including a series of standards carried by 55 said abutment and vertically movable therealong, a channel track secured to the draw and formed with a horizontal intermediate portion, and an upwardly and outwardly 60 inclined end portion, and rollers carried by the gate standards for reception within the horizontal portion of the track when the draw is closed and the standards lowered, the opening of the draw causing said rollers 65 to ride over the inclined portion of the track and raise the gate standards.

3. In a draw-bridge having a draw and an abutment, plates secured to the abutment and having their vertical edges spaced apart, 70 gate standards slidable between said vertical edges of the plates, a channel track secured to the draw and having a horizontal portion and an upwardly and outwardly inclined end portion, and means carried by the gate 75 standards for reception within the horizontal portion of the track when the draw is closed and the standards are in lowered position, the opening of the draw causing the inclined portion of the track to ride against 80 said means and raise the gate standards.

4. In a draw-bridge having a pivoted draw and an abutment, plates secured to said abutments and having their vertical edges spaced apart, gate standards vertically 85 movable between said plates, gravity dogs pivoted to the plates and adapted to hold the standards in their raised positions, rollers secured to said standards and projecting laterally therefrom, and a channel track secured to the draw and having a horizontal portion and an upwardly and outwardly inclined end portion, said rollers being received within the horizontal portion of the track when the draw is closed and the standards lowered, the opening of the draw bringing 95 the inclined portion of the track into engagement with the rollers and raising the gate standards.

In testimony whereof we affix our signatures in presence of two witnesses.

EMIL LINDBERG.

GEORGE C. STEFFAN.
